Application March 12, 1949, Serial No. 81,146

11 Claims. (Cl. 103—135)

1

This invention relates to power transmissions, and is particularly applicable to those of the type comprising two or more fluid pressure energy translating devices, one of which may function as a pump and another as a fluid motor.

The invention relates generally to rotary fluid pumps and in particular to those of the vane type.

One of the major problems encountered in designing rotary pumps is that of providing proper clearance between the rotor faces, and the surfaces against which they rotate. There should be a slight clearance in order for the rotor to run freely but the clearance should not be too high because of decreasing the volumetric efficiency of the pump. Where the abutting surfaces are stationary, the parts must be machined to very close tolerances and in spite of maintaining close manufacturing tolerances leakage will increase as the operating pressure increases and with changes in viscosity of the fluid medium.

One method for maintaining proper rotor clearances is the providing of a floating cheek plate and utilizing fluid pressure from the outlet side of the pump against the cheek plate to adjust the clearance between the rotor and bearing surfaces. This increases the cost of the pump somewhat because of intricate porting and cooperative passages which must be provided in the casing of the pump. In many cases, because of the cheek plate being mounted on the shaft, separate means must be provided to overcome friction tending to prevent the bushing from properly functioning.

It is an object of this invention to provide an improved, simplified, rotary fluid pump having a floatably mounted, pressure responsive cheek plate for maintaining proper rotor clearances.

It is another object of this invention to provide an improved, simplified, low cost rotary vane pump. This has been accomplished without sacrificing efficiency by retaining basic pumping elements well known in the art and utilizing in combination therewith a low cost end cap member which cooperates with a simplified casing member to reduce the total number of parts formerly necessary. The end member is provided with an open recess which is closed by mounting the end cap member against the pumping unit. In this manner, a fluid delivery chamber is formed which lies immediately adjacent the pumping elements and in which the cheek plate may be mounted.

One feature of the pump is the advantage of having inlet passages completely on one side of the rotor of the pumping unit while the outlet

2

passage is completely on the other side of the rotor. The inlet passages lead directly to the suction side of the pumping elements and the outlet passage is connected to the fluid delivery chamber. The cheek plate is provided with dual function porting operating as fluid distributing ports in connecting the delivery side of the pumping unit to the outlet and which also directs fluid pressure to the fluid delivery chamber which is utilized for maintaining the cheek plate in fluid sealing engagement against the rotor.

Another important feature of the pump is the mounting of the drive shaft in the casing completely on one side of the rotor, thus obviating the necessity of a plurality of shaft mounting bores which must be concentric and in strict axial alignment. Properly spaced, combined radial and thrust bearings are placed in the casing member within which the shaft is mounted so as to make the latter capable of receiving thrust and radial loads of gears, chain pulley drives, and other various driving units.

One of the most important features of the pump is the provision of a novel cheek plate designed to cooperate in providing proper rotor clearance. The cheek plate is centrally imperforate and the peripheral edge of the plate is maintained against a portion of a cam ring within which the rotor is mounted. The rotor thickness is slightly less than that of the cam ring to provide a clearance between the rotor and the cheek plate. The entire opposite surface of the cheek plate is exposed to fluid pressure in the delivery chamber. The cheek plate is constructed of a material and so designed as to permit a slight deflection toward the rotor upon increases of pressure in the delivery chamber. The line of deflection and amount thereof may be controlled from the modulus of elasticity of the material selected by providing a thickness and shape of the plate to give the result desired. In this manner a tolerance for wear may be originally provided for and in addition, volumetric efficiency of the pump maintained over a wide pressure range.

It is thus another object of this invention to provide a simplified low cost structure of the aforementioned type having certain advantages contributing to efficiency, reliability, and long life as well as ease of maintenance.

Further objects and advantages of the present invention will be apparent from the following description, reference being had to the accompanying drawings wherein a preferred form of the present invention is clearly shown.

In the drawings:

Figure 1 is a sectional view of a preferred form of the present invention taken on line 1—1 of Figure 3.

Figure 2 is a planned view of the present invention.

Figure 3 is a view taken on line 3—3 of Figure 1.

Figure 4 is a fragmentary view of Figure 1 showing rotor clearance in exaggerated form.

Figure 5 is a view similar to that of Figure 4 but showing rotor clearance upon deflection of the cheek plate.

Figure 6 is a view taken on line 6—6 of Figure 1.

Figure 7 is a view taken on line 7—7 of Figure 1.

Referring to Figure 1 there is shown a rotary vane pump 10 comprising a pumping unit indicated generally by the numeral 12 mounted between an inlet casing member 14 and an end cap member 16.

The pumping unit 12 comprises a cam ring 18 within which, as is shown in Figure 6, is mounted a hubless rotor 20 carrying vanes 22 which reciprocate in slots 24 and the ends of which are maintained by pressure fluid against the approximately oval shaped inner surface 26 of the cam ring 18 which forms a track for the vanes. With the rotor 20 mounted within the cam ring 18 two opposing working chambers 28 and 30 are formed through which the vanes pass as the rotor turns. These chambers may be appropriately divided into fluid intake zones and fluid delivery zones, the former of which comprise that portion of the chambers 28 and 30 registering with inlet openings 32 of the casing member and the latter of which comprise that portion of the chambers registering with outlet openings 34 of a cheek plate 36 (Figure 7) floatably mounted in the end cap 16. Referring to Figure 1, the rotor 20 is driven by a shaft 38 rotatably supported solely within the inlet casing member 14 by means of spaced apart, radial and thrust bearings 40 and 42. The pump is hydraulically balanced because the bearing loads imposed are cancelled out by equal and opposing radial hydraulic thrust loads. The shaft 38 is operatively connected to the rotor 20 by means of a splined connection indicated by the numeral 44. The spline on the shaft fits the spline in the rotor with only a very small clearance so that the shaft acts as the locating means for the rotor radially and yet permits a slight amount of play for the rotor to take up a position flatly against the face of the casing member 14 even though it be not perfectly square with the shaft.

The casing member 14 is provided with an external inlet port 46 having a passage 48 leading directly therefrom to which is connected the inlet openings 32, the latter of which register with that portion of the working chambers 28 and 30 described as the fluid intake zones. An oil seal, indicated generally by the numeral 50, is provided to prevent shaft leakage.

The end cap member 16 is provided with an external outlet port 52 leading directly to an open recess which is closed by the cam ring 18 and the rotor 20 to form a fluid delivery chamber and which, for the purposes of convenience, will be indicated generally by the numeral 54. The end cap member 16 and the casing member 14 are provided with flat end surfaces to cooperate with the opposing flat mating surfaces of the pumping unit 12. As shown in Figure 2 the casing member 14 and the end cap member 16 are

connected to the cam ring 18 and to each other by means of suitable screws 56.

The cheek plate 36 is prevented from rotary movement by means of two dowel pins, which are indicated by the numerals 58, inserted through the cheek plate 36 and extending through the cam ring 18 into the casing member 14. The dowel pins also serve to provide accurate alignment means for changing the relative position of the pumping elements when the direction of shaft rotation is reversed. The outlet openings 34 of the cheek plate 36 extend completely through the plate and as the openings on one side of the plate register with the fluid delivery zones of the working chambers 28 and 30, fluid is pumped directly through the openings into the fluid delivery chamber 54.

The cheek plate 36 is adapted to be maintained in fluid sealing engagement against a portion of the cam ring 18 and the rotor 20 by means of fluid pressure in the fluid delivery chamber 54. Thus, the ports 34 of the cheek plate 36 serve a dual function. They connect the delivery side of the pump directly to the chamber 54, the latter of which is connected to the external delivery port 52. In this manner they function as pump delivery distributing ports and deliver pressure fluid to the chamber for maintaining the cheek plate against the pumping unit. A spring 60 maintains the cheek plate 36 against the cam ring 18 and the rotor 20 during standby or starting periods.

Pressure fluid from the outlet side of the pump is delivered to a groove 62 of the rotor 20 through a plurality of holes 64 extending through the cheek plate 36. The slots 24 of the rotor 20 within which the vanes reciprocate are mounted at their bottom ends as indicated by the numeral 66 and communicate with the groove 62. In this manner pressure fluid from the delivery chamber 54 is delivered through the cheek plate holes 64 to the rotor groove 62 and to the bottom of the slots 24 in order to maintain the outer ends of the vanes 22 in contact with the inner periphery 26 of the cam ring 18.

An inlet flange 68 and an outlet flange 70 may be suitably connected, respectively, to the casing member 14 and the outlet end cap member 16.

Suitable oil seals 72 and 74 are provided in the casing member 14 and end cap member 16 adapted to be on opposite sides of the cam ring 18 to aid in sealing the outlet from the inlet side of the pump and to prevent seepage.

The inlet casing member 14 is provided with a flat end surface indicated by the numeral 76 which serves as an end wall adapted to cooperate with the flat mating surfaces of the cam ring 18 and rotor 20. The end cap member 16 is also provided with a flat surface at the open recess end thereof indicated by the numeral 78 which cooperates with the opposing flat mating surfaces of the cam ring 18 and rotor 20. The cheek plate 36 is designed to fit in the delivery chamber 54 so as to prevent leakage with the cooperation of the seal 74.

The entire surface of the cheek plate opposite to that facing the cam ring 18 and rotor 20, and indicated by the numeral 80, is exposed to outlet pressure in the delivery chamber 54, in order to maintain the cheek plate in fluid sealing engagement against the cam ring and rotor. Running clearance between the rotor 20 and the surface of the cheek plate 36 facing the rotor 20, said surface being indicated by the numeral 82, is provided by the difference in thickness between

the cam ring and that of the rotor. The amount of running clearance is dependent upon the design of the cheek plate and the material of which it is constructed but is on the order of a thousandth of an inch. It should be noted that the sole support against rightward movement is that provided by a portion of the cam ring 18 against which the peripheral edge of the cheek plate is forced by pressure fluid in delivery chamber 54. The remainder of the cheek plate is entirely unsupported against rightward axial movement because of the clearance provided between the rotor and the cheek plate, said clearance being shown in greatly exaggerated form in Figure 4. The cheek plate 36 is comprised of a material such as cast iron, aluminum alloy or bronze, and is designed to provide a predetermined deflection of its unsupported surface as a function of the pressure existent at the outlet side of the pumping unit. The line of deflection and amount thereof may be accurately controlled by designing the shape and thickness of the plate in relation to the type of material of which the plate is constructed and considering also the size of the pump and the pressures to which it will be subjected. The modulus of elasticity of different materials, such as cast iron, which the cheek plate of the present invention is preferably constructed because of its low cost, is known and the line of and amount of deflection may be controlled by designing the plate to meet any application. Thus, the thickness of the plate is determined to a certain extent, upon the original clearance between the rotor and the plate. The larger the clearance, the thinner the plate will be made to provide for more deflection.

The volumetric efficiency of the pump may be controlled by determining the thickness of the plate in relation to the clearance. Thus, the volumetric efficiency of pumps operating over a wide pressure range may be maintained substantially constant by slightly increasing the rotor clearance and utilizing a slightly thinner plate. Figure 5 illustrates deflection of the cheek plate 36 caused by increased operating pressure, the rotor clearance of which has been greatly exaggerated for purposes of illustration.

When the desired direction of rotation of the drive shaft 38 is to be reversed, the cam ring 12 and rotor 18 together with the vanes 22 are turned over end for end so that screw holes 82, 84, 86, and 88 in the cam ring 18 which formerly registered, respectively, with screw holes 90, 92, 94, and 96 in the casing member 14 register, respectively, with the casing holes 92, 90, 96, and 94. The dowel pins 58, which are located on a diameter 45° from the axes of the cam ellipse, accurately align the pumping elements so that the inlet openings 32 of the casing member and the outlet ports 34 of the cheek plate register, respectively, with the fluid intake and fluid delivery zones of the pumping chambers 28 and 30. They also prevent errors in reassembly when shaft rotation is to be reversed. However, they are not essential for preventing errors in reassembly when an alternate form of construction such as is shown in dotted lines in Figure 6 is utilized. Where intersecting lines drawn from the axis of the holes 82, 84, 86, and 88 form a square, it is preferred that the dowel pins be utilized to prevent errors in reassembly when reversing rotation which would incorrectly displace the major axis of the cam ring recess 26. Where, however, the location of the holes in the cam ring, casing member, and end cap member are, as shown in

dotted lines, in Figure 6, in an intersecting relationship, then the screws 56 will serve the dual function of not only connecting the casing member, cam ring, and end cap member together but also will prevent errors in reassembly of the members. Likewise, the screws may be located at the corners of a square, but the outline of the cam ring, casing member, and end cap may be made rectangular, as shown in dotted lines in Figure 6, to avoid such errors. The important requirement is only that the aligning means, such as the dowels, the screws, or the body outlines be symmetrically disposed about a diameter 45° from the major and minor axis of the cam ellipse.

In operation, fluid will be withdrawn by the pump from a suitable supply source into the inlet port 46 and passage 48 from whence it will be delivered by means of the inlet openings 32 to the fluid intake zones of the working chambers 28 and 30. As the rotor turns, the vanes will carry the fluid through the working chambers 28 and 30 to the fluid delivery zones thereof where it will be delivered through the delivery ports 34 of the cheek plate to the fluid delivery chamber 54 and thence to the outlet port 52.

The entire surface 80 of the cheek plate 36 is exposed to fluid pressure in the delivery chamber 54 to maintain proper rotor clearance.

As shown in exaggerated form in Figure 4, the outer periphery of cheek plate 36 will be maintained in fluid sealing engagement against a portion of the cam ring 18. The original rotor clearance remains undisturbed at low pressures. However, as the pressure at the outlet port 52 increases, the corresponding increases of pressure in the delivery chamber 54 acting over the remaining unsupported surface 80 of the cheek plate 36 will deflect the cheek plate toward the rotor as shown in Figure 5 and reduce the rotor clearance.

Due to the fact that the entire surface 80 is exposed to pressure in the delivery chamber 54 while the surface facing the rotor is exposed not only to delivery pressure but also inlet pressure, a differential of forces is established highly in favor of those acting on the surface 80. As the pressure increases in the delivery chamber 54, the deflection of the cheek plate is increased to further decrease the rotor clearance and maintain volumetric efficiency of the pump.

There is thus provided a vane pump which is not only more efficient than predecessors of this type, but which has been greatly reduced in cost. The construction obviates the necessity of having bearing plates on both sides of the rotor. It eliminates the necessity of mounting the cheek plate on the shaft or of providing mounting bearings therefor to prevent loss of efficiency due to friction. The low cost end member permits mounting of the cheek plate in a chamber conveniently adjacent to the rotor. The end cap member is easily removable for replacement of a new cheek plate and in addition the casing member and end cap member may serve continually with replacement pumping elements, namely, the cam ring, rotor, and vanes.

The construction also permits the inlet passages being on one side of the rotor and leading directly to the fluid intake zones of the pumping unit while the dual function outlet porting in the cheek plate directly connects the fluid delivery zones of the pumping unit and the delivery chamber to the outlet passage on the opposite side of the rotor.

While the form of embodiment of the invention as herein disclosed constitutes a preferred form, it is to be understood that other forms might be adopted, all coming within the scope of the claims which follow.

What is claimed is as follows:

1. In a rotary pump, the combination of a housing having a pumping chamber, pumping mechanism mounted in the chamber including means forming a fluid inlet zone and a fluid outlet zone, an inlet passage in the housing completely on one side of the pumping mechanism and leading to the fluid inlet zone, an end member having an open recess and an outlet passage connected thereto and mounted against the housing on the other side of the pumping mechanism to close the recess and form a fluid delivery chamber, and a centrally imperforate cheek plate floatably mounted in the fluid delivery chamber and having an outlet opening extending therethrough registering with the fluid outlet zone, said cheek plate being maintained in fluid sealing engagement against the pumping mechanism by fluid pressure in the delivery chamber delivered thereto through the cheek plate outlet opening.

2. A rotary vane pump comprising a housing having a pumping chamber, a slotted rotor carrying a plurality of substantially radially movable vanes and mounted in the chamber to form a fluid intake zone and a fluid outlet zone through which the vanes move as the rotor turns, an inlet passage in the housing completely on one side of the rotor and leading directly to the fluid intake zone; an end member having an open recess and an outlet passage connected thereto and mounted against the housing on the opposite side of the rotor to close the recess and form a fluid delivery chamber immediately adjacent the rotor, a pressure responsive, centrally imperforate, cheek plate floatably mounted in the fluid delivery chamber and having an outlet opening extending therethrough registering with the fluid outlet zone, said cheek plate being maintained in fluid sealing engagement against the rotor by fluid pressure in the delivery chamber delivered thereto through the cheek plate outlet opening.

3. In a rotary vane pump, the combination of a housing having a pumping recess, a slotted rotor carrying a plurality of substantially radially movable vanes and mounted in the recess to form a fluid intake zone and a fluid delivery zone through which the vanes move as the rotor turns, an inlet passage and an outlet passage in the housing respectively connected to the fluid inlet zone and the fluid delivery zone, means forming a rigid abutment at one side of the rotor, an elastic, deflectable cheek plate floatably mounted in the recess immediately adjacent the other side of rotor, porting means connecting the fluid delivery zone to the recess on the side of the cheek plate opposite to that facing the rotor, and a rigid shoulder supporting the outer peripheral portion of the cheek plate against the fluid pressure force on said opposite side and forming a running clearance between the rotor and the unsupported surface of the cheek plate facing the rotor, said unsupported surface of the cheek plate being deflected towards the rotor for reducing the running clearance in response to increases of delivery pressure of the pump.

4. In a rotary vane pump, the combination of a housing having a pumping recess, a slotted

rotor carrying a plurality of substantially radially movable vanes and mounted in the recess to form a fluid intake zone and a fluid delivery zone through which the vanes move as the rotor turns, an inlet passage and an outlet passage in the housing respectively connected to the fluid inlet zone and the fluid delivery zone, means forming a rigid abutment at one side of the rotor, an elastic, deflectable cheek plate floatably mounted in the recess immediately adjacent the other side of rotor, porting means connecting the fluid delivery zone to the recess on the side of the cheek plate opposite to that facing the rotor, and a rigid shoulder supporting the outer peripheral portion of the cheek plate against the fluid pressure force on said opposite side and forming a running clearance between the rotor and the unsupported surface of the cheek plate facing the rotor, said cheek plate being comprised of a material, the thickness of which is determined by the modulus of elasticity of the material to provide a predetermined deflection of the unsupported surface of the cheek plate towards the rotor for reducing the running clearance in response to increases of delivery pressure of the pump.

5. In a rotary vane pump, the combination of a housing having a pumping recess, a slotted rotor carrying a plurality of substantially radially movable vanes and mounted in the recess to form a fluid intake zone and a fluid delivery zone through which the vanes move as the rotor turns, an inlet passage and an outlet passage in the housing respectively connected to the fluid inlet zone and the fluid delivery zone, means forming a rigid abutment at one side of the rotor, a centrally imperforate elastic, deflectable cheek plate floatably mounted in the recess immediately adjacent the other side of rotor, porting means in the cheek plate connecting the fluid delivery zone to the recess on the side of the cheek plate opposite to that facing the rotor, and a rigid shoulder supporting the outer peripheral portion of the cheek plate against the fluid pressure force on said opposite side and forming a running clearance between the rotor and the unsupported surface of the cheek plate facing the rotor, said unsupported surface of the cheek plate being deflected towards the rotor for reducing the running clearance in response to increases of delivery pressure of the pump.

6. In a rotary pump, the combination of a housing having a pumping chamber, pumping mechanism mounted in the chamber including means forming a fluid inlet zone and a fluid outlet zone, an inlet passage in the housing completely on one side of the pumping mechanism and leading to the fluid inlet zone, an end member having an open recess and an outlet passage connected thereto and mounted against the housing on the other side of the pumping mechanism to close the recess and form a fluid delivery chamber, a cheek plate floatably mounted in the fluid delivery chamber, porting means connecting the fluid outlet zone to the delivery chamber on the side of the cheek plate opposite to that facing the pumping mechanism, said cheek plate being maintained in fluid sealing engagement against the pumping mechanism by fluid pressure in the fluid delivery chamber, and a drive shaft operatively connected to the pumping mechanism mounted and rotatably supported in the housing completely on the inlet side of the pumping mechanism.

7. In a rotary pump, the combination of a

housing member having a pumping recess, pumping mechanism including a rotor mounted in the recess and forming a fluid intake zone and a fluid delivery zone, an inlet passage on one side of the rotor leading directly to the fluid intake zone, an end member having an outlet passage and mounted against said housing member on the opposite side of the rotor to close the recess and form a fluid delivery chamber immediately adjacent the rotor, said housing providing a rigid abutment at one side of the rotor, an elastic deflectable cheek plate floatably mounted in the delivery chamber at the other side of the rotor, porting means connecting the fluid delivery zone to the delivery chamber on the side of the cheek plate opposite to that facing the rotor, a rigid shoulder supporting the outer peripheral portion of the cheek plate against the force of fluid pressure in the delivery chamber and forming a running clearance between the unsupported face of the cheek plate and the rotor, said unsupported surface of the cheek plate being deflected towards the rotor for reducing the running clearance in response to increases of delivery pressure of the pump, and a drive shaft operatively connected to the rotor and rotatably supported in the housing completely on one side of the rotor.

8. A rotary vane pump comprising a slotted rotor carrying a plurality of substantially radially movable vanes, a cam ring of generally elliptical inner contour surrounding the rotor to form diametrically opposite pairs of fluid intake zones and fluid delivery zones through which the vanes move as the rotor turns, a pair of housing members, one having means providing a single pair of inlet openings adjacent an end face of the rotor and ring and extending arcuately along said intake zones and the other member having a chamber adjacent the opposite end face of the rotor and ring, said one housing member having an external inlet port in communication with said inlet openings, said other housing member having an external outlet port communicating with said chamber and a floating side plate in said chamber normally contacting the ring and rotor, said plate having a single pair of outlet openings therethrough extending arcuately along said outlet zones.

9. A rotary vane pump comprising a slotted rotor carrying a plurality of substantially radially movable vanes, a cam ring of non-circular inner contour surrounding the rotor to form equally spaced sets of fluid intake zones and fluid delivery zones through which the vanes move as the rotor turns, a pair of housing members, one having means providing inlet openings adjacent an end face of the rotor and ring and extending arcuately along said intake zones and the other member having a chamber adjacent the opposite end face of the rotor and ring, said one housing member having an external inlet port in communication with said inlet openings, said other housing member having an external outlet port communicating with said chamber and a floating side plate in said chamber normally contacting the ring and rotor and having outlet openings therethrough extending arcuately along said outlet zones.

10. A rotary vane pump comprising a central pumping unit having parallel plane sides and including a stationary outer ring and an inner, vane-carrying rotor, together providing a plurality of fluid intake zones and a plurality of fluid delivery zones, a main base member abutting one side of the unit and comprising a thick

block having only inlet passages therein and a shaft connected with the rotor and journaled in said block, a housing member secured to the opposite side of the pumping unit and having a fluid outlet connection and a chamber enclosing the rotor and a portion of the face of the ring, a floating cheek plate mounted in the chamber to abut the face of the rotor and ring, and outlet ports formed in the cheek plate to carry the entire fluid delivery from the pumping unit, through the chamber and into the outlet, said block providing a rigid base with a plane face which is relatively free from distortion under fluid pressure loads and against which the cheek plate may urge the rotor and vanes under the pressure of the fluid being delivered through said chamber.

11. A rotary vane pump comprising a central pumping unit having parallel plane sides and including a stationary outer ring and an inner, vane-carrying rotor, together providing a plurality of fluid intake zones and a plurality of fluid delivery zones, a main base member abutting one side of the unit and comprising a thick block of solid metal having a single axial bore forming a shaft journal mounting, a single transverse bore forming an inlet connection and having perpendicular branches extending to said intake zones, and a shaft connected with the rotor and journaled in said block, a housing member secured to the opposite side of the pumping unit and having a fluid outlet connection and a chamber enclosing the rotor and a portion of the face of the ring, a floating cheek plate mounted in the chamber to abut the face of the rotor and ring, and outlet ports formed in the cheek plate to carry the entire fluid delivery from the pumping unit, through the chamber and into the outlet, said block providing a rigid base with a plane face which is relatively free from distortion under fluid pressure loads and against which the cheek plate may urge the rotor and vanes under the pressure of the fluid being delivered through said chamber.
